(57) **CLAIM**

The ornamental design for an automobile, as shown and
described.

DESCRIPTION

FIG. 1 is a front view of an automobile in accordance with
the present invention;

FIG. 2 is a rear view thereof;

FIG. 3 is a side view thereof; and,

FIG. 4 is a top view thereof.

The broken lines in the drawing views are shown for
illustrative purposes only and form no part of the claimed
design.
